[57] CLAIM

The ornamental design for a device for delivering cards, as shown and described.

DESCRIPTION

FIG. 1 is a first perspective view of a first embodiment of the present invention showing our new design;

FIG. 2 is a second perspective view thereof;

FIG. 3 is a rear elevational view thereof;

FIG. 4 is a front elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a first perspective view of a second embodiment of the present invention showing my new design;

FIG. 10 is a second perspective view thereof;

FIG. 11 is a rear elevational view thereof;

FIG. 12 is a front elevational view thereof;

FIG. 13 is a left side elevational view thereof;

FIG. 14 is a right side elevational view thereof;

FIG. 15 is a top plan view thereof; and,

FIG. 16 is a bottom plan view thereof.
